PROCESS OF REFINING ANIMAL AND
VEGETABLE OILS

Benjamin Clayton, Houston, Tex., and Benjamin H. Thurman, Bronxville, N. Y., assignors to Refining, Inc., Reno, Nev., a corporation of Nevada

Application November 15, 1937, Serial No. 174,720

12 Claims. (Cl. 260—425)

This invention relates to a process of refining animal and vegetable oils and more particularly to a process employing an agent which opposes or breaks the emulsion which tends to form when a refining reagent is mixed with the oil, such that elevated temperatures with their increased refining losses are not required.

In the refining of vegetable and animal oils, a refining reagent, which is ordinarily an aqueous solution, is mixed with an oil containing impurities so as to react with the impurities to render the same separable from the oil by difference in specific gravity. An emulsion, which is apparently of the water and oil type, tends to form during such mixing and it is necessary to break or prevent the formation of such an emulsion before adequate separation can be effected. In conventional processes the breaking of the emulsion has been accomplished by elevating the temperature of the mixture prior to separation. Thus temperatures between, for example, 100° and 160° F. and usually between 115° and 145° F. have been employed to break the emulsion so that the foots produced by treating the oil with the refining reagent will settle from the oil or can be centrifugally separated therefrom. The refining reagents employed will, in general, also attack the oil as well as impurities contained therein, and this attack upon the oil is increased by the elevated temperatures so that refining losses are increased or the quality of the oil decreased.

In accordance with the present invention, an agent is employed which will either oppose the formation of or break the usual emulsion without the necessity of ever having the mixture at the emulsion breaking or opposing temperatures above mentioned. Only sufficient heat is necessary to cause the oil to be in a flowable condition and unnecessary refining losses or injury to the oil are largely prevented.

It is, therefore, an object of the invention to provide a process of refining animal and vegetable oils in which an emulsion opposing or breaking agent is employed.

Another object of the invention is to provide a process of refining animal and vegetable oils in which separation of foots from the oils is effected at relatively low temperatures.

A further object of the invention is to provide a process of refining animal and vegetable oils in which an emulsion opposing or breaking agent is present during mixing of the oil with a refining reagent.

While an emulsion, such as discussed above,

tends to form in almost any type of refining, including so-called partial refining or degumming, the most stable emulsions are ordinarily formed in alkali refining. In alkali refining, a solution of an alkaline reagent, for example, caustic soda, is employed to neutralize the free fatty acids of the oil and form foots including soap stock. The soap is an effective emulsifying agent, producing very difficultly separable emulsions, particularly if the mixing is carried on at relatively low temperatures. Also, an excess of the refining reagent is usually employed to reduce the color of the oil such that substantial amounts of neutral oil are saponified if the mixture is produced at, or brought to an elevated temperature sufficiently high to oppose or break the emulsion in the absence of an emulsion breaking agent. The present invention is, therefore, particularly adapted for the alkali refining of animal and vegetable oils although it is advantageous in other types of refining of such oils.

It is, therefore, a still further object of the invention to provide a process of refining animal and vegetable oils with an alkaline reagent in which an emulsion opposing or breaking agent is employed to avoid the necessity of operations at elevated temperatures.

Other advantages and embodiments of the invention will appear in the following description of the invention given with reference to the attached drawing which is a diagrammatic drawing of one form of apparatus suitable for carrying out the present invention.

Referring to the drawing, the apparatus shown is designed for carrying out a continuous process and includes a source of supply for the oil, shown as tank 10, a source of supply for the emulsion breaking agent, shown as a tank 11, a source of supply for the refining reagent shown as a tank 12, a proportioning mechanism indicated generally at 13, a treating coil 14, and a centrifugal 15.

The proportioning mechanism may include a proportioning pump 16 for withdrawing oil from the tank 10 and delivering the same to a mixer 17 for mixing the oil with the emulsion breaking agent. The proportioning device may also include a proportioning pump 18 for withdrawing an emulsion breaking agent from the tank 11 and delivering the same to the mixer 17. The proportioning device may also include a proportioning pump 19 for withdrawing refining reagent from the tank 12 and delivering the same to a mixer 21 for mixing the refining reagent with the oil. The proportioning pumps 16, 18 55

and 20 may be driven by a variable speed electric motor 22 and may have variable speed devices 23 and 24 positioned between the various pumps so that the proportions of the oil, emulsion breaking agent and refining reagent can be varied by changing the variable speed devices 23 and 24 and the total amount of the various materials varied by changing the speed of the motor 22. The particular proportioning device 10 described is merely one way of securing accurately proportioned streams of materials and any other type of proportioning mechanism which will deliver such accurately proportioned streams can be substituted therefor.

15 The mixer 17 may be any suitable type of flow or continuous mixer, for example, a device in which a stream of one material is injected at right angles into the stream of the other material or it may be a mechanical agitator into which 20 the streams of oil and emulsion breaking agent are delivered and the resulting mixture continuously withdrawn. It is preferred to have the oil and emulsion breaking agent thoroughly mixed before admixture with the refining reagent but 25 substantially equivalent results can be accomplished by mixing the emulsion breaking agent with the refining reagent prior to mixing with the oil. This can be accomplished by placing the mixer 17 in the pipe 25 between proportioning 30 pump 20 and the mixer 21 and delivering the stream of emulsion breaking agent to the said mixer. The process can also be simplified by mixing proper proportions of the emulsion breaking agent with the refining reagent in the tank 35 12 so as to eliminate the tank 11, along with proportioning pump 18 and mixer 17. In general, the emulsion breaking agent is more miscible with the refining reagent than with the oil and therefore difficult to mix with the oil, but 40 if an emulsion breaking agent which is miscible with the oil is employed, it can be mixed with the oil in the tank 10 instead of with the refining reagent in the tank 12. If desired, the stream 45 of emulsion breaking agent can be delivered directly to the mixer 21 so that streams of oil, emulsion breaking agent, and refining reagent, are mixed in a single mixer. It is preferred to have the emulsion breaking agent present during the mixing of the oil and refining reagent 50 so as to oppose the formation of an emulsion, but advantageous results can be secured by mixing the emulsion breaking agent with the mixture resulting from contacting the oil and refining reagent. Thus, a stream of emulsion 55 breaking agent can be introduced into the mixture promptly after the oil and refining reagent have been contacted. In any case, a difficulty separable emulsion is prevented from forming or such an emulsion is immediately broken after 60 its formation.

Mixing of the oil and refining reagent results in a mixture of oil and foots which, in the case of alkali refining, is predominantly soap stock. Due to the presence of the emulsion breaking 65 agent, the mixture of oil, foots and emulsion breaking agent, is in condition for immediate centrifugal separation but in many types of refining, particularly alkali refining, it is desirable to provide additional time of contact between the oil and refining reagent in order to reduce 70 the color of the oil. During this additional time, the refining reagent can act upon color impurities and adsorption of the reacted color impurities by foots effected. A convenient device for this purpose is a pipe coil such as the coil 14.

75

The mixture should be kept in sufficient state of movement to prevent stratification of the foots so that a substantially uniform mixture of oil and foots is maintained. This is particularly important when centrifugal separation is employed as stratification with the resultant delivery of large masses of foots to the centrifugal will result in imperfect separation by causing foots to be discharged with the oil. The movement of the oil or mild agitation thereof enables the particles of foots to repeatedly contact reacted color impurities in the oil such that they are adsorbed by, or otherwise combined with the foots. As stated above, the coil is an effective mechanism for this purpose but any other type of treating 15 device, such as a mechanical agitator, which will provide proper movement of the mixture without breaking up of the particles of foots can be employed instead of the coil. If color removal is unnecessary or not desired, the mixture of 20 oil and foots may be delivered directly to a suitable separating device such as a centrifugal separator 15.

The centrifugal separator 15 may be any suitable type of continuous centrifugal separator 25 employing a rotating bowl from which the foots are separated from the oil by differences in specific gravity and the employment of centrifugal force. The oil constitutes the lighter effluent and may be discharged from the centrifugal through 30 a spout 26 into an oil receiver 27. The type of emulsion breaking agents contemplated by the present invention substantially all separate with the foots as the heavier effluent which is discharged through a spout 28 into a foots receiver 35 29. While any suitable type of centrifugal can be employed, the heated centrifuge disclosed in the copending application of Benjamin Clayton, Serial No. 34,258, filed August 1, 1935, is preferred 40 as a more uniform delivery of the heavier effluent can in most cases be secured by preventing the building up of layers of adherent material 45 upon the walls of the centrifugal bowl.

It is unnecessary to use elevated temperatures in the present process but the oil must be of 45 sufficient fluidity to provide for adequate mixing and for passage through the process. For this purpose the oil tank 10 may be provided with a heating coil 30 through which any desired heating medium, such as hot water or steam, can be 50 passed in order to bring the oil to the required temperature. This temperature will vary with the type of oil being treated but will usually fall between temperatures of 70° to 95° F. To prevent chilling of the oil due to admixture there- 55 with of cold refining reagent or emulsion breaking agent, similar heating coils 31 and 32 may also be positioned in the tanks 11 and 12, respectively. In order to simplify the apparatus it is sometimes possible to heat only the oil to a 60 somewhat higher temperature than those indicated such that mixing relatively cool refining reagent or emulsion breaking agent therewith will not cool the oil below its flow temperature. This enables the heating coils 31 and 32 to be eliminated. In some cases it is found that mixing may be at a relatively low temperature but that better color reduction or separation is accomplished at a somewhat higher temperature. In such cases the mixture may be heated in the 70 treating device 14 as by surrounding the coil thereof with a heating jacket 33 through which any desired heating medium may be passed. The application of heat to the coil 14 is usually unnecessary and the temperature necessary to be 75

reached therein will rarely exceed 100° F. as 5 breaking of the emulsion or the prevention of its formation is accomplished primarily by the emulsion breaking agent. With certain oils it is sometimes desirable to mix at a higher temperature than that necessary for separation in which case the oil may be somewhat cooled in the coil 14 or other treating device by passing a cooling medium through the jacket 33. Separation can 10 ordinarily be accomplished at temperatures ranging between substantially 70° F. and 100° F. although it may be advantageous with certain oils to increase the temperature of the heavier effluent in the centrifugal by the employment of 15 the heated centrifuge above mentioned.

The preferred emulsion breaking or opposing agents, in accordance with the present invention, are concentrated solutions of salts which have substantially no reaction with the oil being 20 refined. Such salts should have high solubility in water and examples are sodium chloride or sodium sulfate. While such substantially neutral salts are preferred, it is, of course, possible to use salts having an alkaline reaction such as 25 sodium carbonate or silicate in the alkali refining. With acid refining, salts having an acid reaction may be employed. In general, water soluble alkali metal salts having no deleterious reaction upon the oils, can be employed. Such 30 salts also have a valuable salting out or separation promoting function but, in general, greater proportions must be employed in the present invention, where elevated temperatures are not employed and the emulsion breaking agent is 35 depended upon to break the emulsion, than those necessary to merely promote separation of foots from an already broken emulsion. Thus concentrated salt solutions ranging from 3% to 15%, depending upon the nature of the oil being refined 40 and the type of oil being employed, have been found suitable. The salt solutions are either present during mixing or added immediately thereafter.

It has also been found that certain alcohols, 45 such as ethyl, butyl, iso-propyl and amyl, can be employed as the emulsion breaking agent and also certain esters of these alcohols, for example, the acetic esters, will prevent the formation of an emulsion or break the same after it is formed. 50 Such alcohols or esters also have valuable saponification inhibiting and anti-sticking functions even when elevated temperatures are employed for breaking the emulsion but, in general, greater proportions than those necessary to inhibit saponification and sticking must be employed in the present process, where elevated 55 temperatures are not employed and the breaking of the emulsion or the prevention of its formation is accomplished by the emulsion breaking agent. No exact proportions can be given as the amounts necessary will vary with the quality and type of oil and the type of refining, but in general from 3% to 15% of alcohol or ester or relatively concentrated solutions thereof are 60 effective.

With any type of emulsion breaking agent, the proportions employed depend upon the amount of impurities in the oil and the type of refining employed. Oils having large amounts of impurities usually require larger amounts of emulsion breaking agent and in general larger proportions are necessary for alkali refining than for acid refining or degumming. In alkali refining the usual refining reagents known to the art and in 65 the proportions conventionally used can be em-

ployed in the present invention. That is, sufficient refining reagent is employed to neutralize the free fatty acids and give a considerable excess for reaction with color impurities. The foots produced are predominantly soap stock and constitute along with gums present in the oil an excellent emulsifying agent such that sufficient emulsion breaking agent should be employed to effectively oppose or break any emulsion which might tend to form. Alkali refining is ordinarily 10 employed with oils intended for edible purposes, such as cottonseed, rape seed, soya bean, etc., although in some cases alkali refining is employed for drying oils, such as linseed oil, fish oils, or soya bean oil intended for drying oil use. 15

In acid refining, the refining reagent is ordinarily a relatively concentrated sulfuric acid, although other acids, such as hydrochloric acid, can be employed. A usual acid refining reagent is 60 Baumé sulfuric acid in amounts between 20 1% and 3% depending upon the amount of impurities in the oil. The acid refining agent does not remove free fatty acids but acts upon gums and other impurities in the oil to render them separable from the oil as acid foots probably by 25 dehydration or carbonization reactions. Difficultly separable emulsions are frequently encountered which can be broken or prevented from forming by the emulsion breaking agents of the present invention.

In partial refining or degumming, water can be employed to render gums separable as foots from the oil, probably by a hydration reaction. Very dilute solutions of salts, acids and alkalies, have been employed for degumming, but the acid 30 and alkali solutions were of such small concentration as to have no appreciable reaction with the oil or impurities therein and the salt, when used, was present in such small amount as to have no appreciable effect upon the emulsion which tends to form when water is mixed with 40 oil. By adding a concentrated salt solution or the alcohols or esters of the present invention, no emulsion is formed or it is immediately broken. Since the emulsion breaking agents ordinarily contain water it is many times not necessary to add any other water than that contained 45 in the emulsion breaking agent so that the oil is degummed with relatively concentrated salt, alcohol or ester solutions. Such partial refining 50 may be carried on in the apparatus disclosed and the degummed oil delivered to a duplicate apparatus for performing either an acid or alkali refining such that the impurities in the oil are recovered in separate portions. The foots from 55 the degumming operation on certain oils, particularly hot pressed vegetable oils, are largely valuable phosphatides in relatively pure form and the foots from the second or more complete refining are relatively free from phosphatides. Thus, 60 the soap stock from alkali refining is in purer and more valuable form.

Any of the refining reagents herein disclosed react with the oil as well as the impurities therein at elevated temperatures. The alkali reagents 65 saponify neutral oil, causing unnecessary refining loss while the acid reagents sulphonate, chlorinate or otherwise react with the oil depending upon the type of acid used, rendering the oil unfit for many purposes. Even water may cause 70 splitting of the oil at elevated temperatures. The present invention, therefore, provides a refining process for animal and vegetable oils which makes it unnecessary to employ elevated temperatures for extended periods of time.

destruction of refined oil is, therefore, largely prevented.

It will be noted that the particular apparatus disclosed provides a closed system from the entrance of the various materials into the process to the separation step such that air is excluded during the process. A closed mixing zone is preferred, particularly if considerable agitation is employed during mixing, as air may be beaten into the mixture to cause a more difficultly separable emulsion so as to require the employment of excessive amounts of emulsion breaking or opposing agent. In the present process the mixture is immediately conditioned for separation such that the entire process may be performed in a few minutes for example, mixing may take from less than 1 minute up to 5 minutes, and separation not more than 3 minutes so that the entire process may take not more than from 4 to 8 minutes. If a longer treating time is required for color removal, such additional time will usually range from 2 to 5 minutes and will rarely exceed 10 minutes such that the entire process will rarely exceed 15 to 18 minutes, and will usually require not more than 5 to 10 minutes. Since refining losses or other attacks on the oil by the refining reagent increase with time as well as temperature it is desirable to perform the process in as short time and at as low temperature as the nature of the oil and refining process permits. By employing emulsion opposing or breaking agents as herein disclosed, a quick process at low temperatures can be employed to minimize refining losses and reactions with the purified oil.

35 Salt solutions separated with the foots can ordinarily be separated therefrom by decantation or centrifugal separation, and many times can be reused in the process with or without purification. Alcohol or esters thereof separated with the foots can be recovered for reuse by vaporization and condensation and the same is true of any of such materials which are present in the purified oil separated from the foots.

45 The term "vegetable and animal oils" as employed herein is intended to embrace and include oils and fats of the same general type as those specifically mentioned herein including fish oils.

50 While the preferred embodiments of the invention have been disclosed, it is understood that the invention is not limited to the details thereof but may be varied within the scope of the following claims.

55 We claim:

1. The process of refining vegetable and animal oils, which comprises, mixing said oils with a refining reagent at a relatively low temperature which is sufficiently high that the oil is flowable but which is below an emulsion breaking temperature, performing said mixing in the presence of an emulsion opposing or breaking agent so as to immediately produce a mixture of oil and foots conditioned for separation and thereafter centrifugally separating said foots from said oil.

60 2. The process of refining vegetable and animal oils, which comprises, mixing said oil with a refining reagent capable of reacting with impurities in said oil to form foots at a temperature sufficiently high that the oil is flowable but insufficient to break the emulsion which tends to form, breaking any emulsion which may tend to form during said mixing by incorporating with said mixture an emulsion opposing or breaking agent so as to condition the mixture for separa-

tion, thereafter centrifugally separating said foots from said oil.

3. The process of refining animal and vegetable oils, which comprises, mixing measured quantities of oil, refining reagent and emulsion breaking or opposing agent at a temperature sufficiently high that the oil is flowable but sufficiently low that emulsion would be formed in the absence of said agent, employing sufficient amounts of said agent to oppose or break said emulsion so as to produce a mixture containing oil and foots in condition for centrifugal separation, thereafter centrifugally separating said foots from said oil.

4. The process of refining vegetable and animal oils, which comprises, mixing a measured quantity of said oil with a measured quantity of a refining reagent at a temperature at which the oil is flowable but below an emulsion breaking temperature, performing said mixing in the presence of an emulsion opposing or breaking agent so as to form a mixture containing oil and foots in condition for centrifugal separation, maintaining said mixture for a time sufficient to provide for reaction of said reagent upon color impurities and promptly thereafter centrifugally separating said foots from said oil.

5. The process of refining animal and vegetable oils, which comprises, mixing a measured quantity of said oil with a measured quantity of a refining reagent at a temperature sufficiently high to cause said oil to be in a flowable condition but below the temperature at which the emulsion which tends to form during said mixing would be broken, incorporating an emulsion breaking or opposing agent in said mixture so as to condition said mixture for prompt centrifugal separation and promptly centrifugally separating the foots formed during said mixing from said oil.

6. The process of refining animal and vegetable oils, which comprises, mixing measured quantities of said oil with measured quantities of a refining reagent at a temperature at which the oil is flowable but below an emulsion breaking temperature, incorporating in said mixture a sufficient quantity of an emulsion breaking or opposing agent to condition the resulting mixture for centrifugal separation and promptly thereafter centrifugally separating said oil from the resulting sludge.

7. The process of refining animal and vegetable oils, which comprises, mixing measured quantities of oil with measured quantities of alkaline refining reagent at a temperature at which the oil is flowable but below an emulsion breaking temperature to form a mixture containing oil and soap stock, incorporating with said mixture sufficient emulsion opposing or breaking agent to condition said mixture for centrifugal separation, and promptly thereafter centrifugally separating said soap stock along with said agent from said oil.

8. The process of refining animal and vegetable oils containing free fatty acids and color impurities, which comprises, mixing measured quantities of oil and alkaline refining reagent at a temperature at which the oil is flowable but below an emulsion breaking temperature to form a mixture containing oil and soap stock, incorporating sufficient emulsion opposing or breaking agent in said mixture to condition the resulting mixture for immediate centrifugal separation, passing said mixture to a centrifugal separator while providing sufficient time for excess refining reagent to act on said color impurities, maintaining said mixture during said pas-

- sage in sufficient state of movement to prevent stratification of said soap stock and promptly centrifugally separating said soap stock along with said agent from said oil.
- 5 9. A quick continuous process of refining animal and vegetable oils, which comprises, mixing small measured quantities of said oil with small measured quantities of a refining reagent at a temperature at which the oil is flowable but below an emulsion breaking temperature, incorporating in said mixture a sufficient quantity of an emulsion breaking or opposing agent to condition the resulting mixture for centrifugal separation and promptly thereafter centrifugally 10 separating said oil from the resulting sludge.
- 10 10. A quick continuous process of refining animal and vegetable oils, which comprises, mixing small measured quantities of oil with small measured quantities of alkaline refining reagent at a temperature at which the oil is flowable but below an emulsion breaking temperature to form a mixture containing oil and soap stock, incorporating with said mixture sufficient emulsion opposing or breaking agent to condition said 15 mixture for centrifugal separation, and promptly thereafter centrifugally separating said soap stock along with said agent from said oil.
11. The process of refining animal and vegetable oils, which comprises, mixing measured quantities of said oil with measured quantities of a refining reagent in a zone closed from the air at a temperature at which the oil is flowable but below an emulsion breaking temperature, incorporating in said mixture a sufficient quantity of an emulsion breaking or opposing agent to condition the resulting mixture for centrifugal separation and promptly thereafter centrifugally 10 separating said oil from the resulting sludge.
12. A quick continuous process of refining animal and vegetable oils, which comprises, mixing small measured streams of said oil with small measured quantities of a refining reagent at a 15 temperature at which the oil is flowable but below an emulsion breaking temperature, incorporating in said mixture a sufficient quantity of an emulsion breaking or opposing agent to condition the resulting mixture for centrifugal 20 separation and promptly thereafter centrifugally separating said oil from the resulting sludge.
